Leo Zweig, San Francisco, Calif., assignor to
Lyons-Magnus, Inc., San Francisco, Calif., a
corporation of Delaware

Application August 1, 1949, Serial No. 4,236

Term of patent 14 years

(Cl. D13—1)

To all whom it may concern:

Be it known, that I, Leo Zweig, a citizen of the United States, residing at San Francisco, in the county of San Francisco and State of California, have invented a new, original, and ornamental Design for a Roadside Stand, of which the following is a specification, reference being had to the accompanying drawing, forming a part thereof.

Figure 1 is a front elevation of a roadside stand, embodying my new design;

Figure 2 is a rear elevation;

Figure 3 is a side elevation; and

Figure 4 is a front perspective view thereof.

I claim:

The ornamental design for a roadside stand, substantially as shown.

LEO ZWEIG.
